US00D994723S

(12) **United States Design Patent** (10) Patent No.: **US D994,723 S**
(45) Date of Patent: ** Aug. 8, 2023

(54) **CONTROL PANEL FOR AN APPLIANCE**

(71) Applicant: **WHIRLPOOL CORPORATION**,
Benton Harbor, MI (US)

(72) Inventors: **Nathan Bilancio**, St. Joseph, MI (US);
Marco Cammarata, Benton Harbor,
MI (US); **Alexander L. Clayton**, St.
Joseph, MI (US); **Estela Duhart**, St.
Joseph, MI (US); **Brandon L. Satanek**,
Stevensville, MI (US)

(73) Assignee: **WHIRLPOOL CORPORATION**,
Benton Harbor, MI (US)

(**) Term: **15 Years**

(21) Appl. No.: **29/858,362**

(22) Filed: **Oct. 31, 2022**

Related U.S. Application Data

(62) Division of application No. 29/703,510, filed on Aug.
28, 2019, now Pat. No. Des. 975,145, which is a
division of application No. 29/589,434, filed on Dec.
30, 2016, now Pat. No. Des. 863,379.
